UNITED STATES PATENT OFFICE.

IRVING W. COLBURN, OF FRANKLIN, PENNSYLVANIA.

GLASS-WORKING MACHINE.

SPECIFICATION forming part of Letters Patent No. 766,932, dated August 9, 1904.

Application filed March 3, 1903. Serial No. 145,876. (No model.)

To all whom it may concern:

Be it known that I, IRVING W. COLBURN, a citizen of the United States, residing at Franklin, in the county of Venango and State of Pennsylvania, have invented certain new and useful Improvements in Glass-Working Machines, of which the following is a specification.

My invention relates to a novel means or apparatus for producing articles of glass.

The object is to furnish a machine that will manufacture cylinders of glass of large size and brilliant surface adapted to be cut off at the ends, slit open, and flattened out into sheets suitable for window-glass.

The machine is also adapted to the formation of cylindrical and spherical receptacles of large size after suitable manipulation.

In the drawings forming a part of this specification, Figure 1 is a side elevation of the machine. Fig. 2 is an elevation, partly in section, showing certain parts turned from the horizontal position of Fig. 1 to a vertical position. Fig. 3 is an end elevation as seen from the left of Fig. 1. Fig. 4 is a plan view. Fig. 5 is an enlarged end view of the upper head. Fig. 6 is an enlarged sectional view of the upper head and plunger. Fig. 7 is an end elevation, partly in section, taken on line C D of Fig. 1. Fig. 8 is an enlarged sectional view of the rotary spindle and air connection.

Referring to said drawings, 1 and 2 are the two side main-frame uprights or supports of the machine, preferably made of flanged castings for strength combined with lightness. These frame-castings are preferably supported on a masonry-base *b* and are held together by through-bolts 103, also bolt 106, which, besides bracing the main frame, has the additional function of forming a stop for the pivoted cradle-frame 3 when in the horizontal position, (shown in Fig. 1,) the bracket 107 on the cradle forming a stop-rest. Said main frame-castings also support the pivoted cradle-frame, and for this purpose the hubs 111 112 are provided at the top of said frames, preferably cast integral therewith. These hubs are properly bored, and bushings 69 70 are fitted tightly therein. The cradle-frame

swings upon these bushings as a pivot, and through the bushings pass concentrically the revoluble shafts 34 35, described below. The cradle-frame carries a head-stock 4, with its various mechanisms, a carriage 6 for the mold 5, and a movable tail-stock 5, carrying the mechanisms hereinafter described. Besides the cradle-frame and the shafting above mentioned the said main frames carry the attached brackets 29 26 27 28, which form bearings for revoluble shafts 22 23. Shaft 22 carries bevel-gear 30, which meshes with bevel-gear 32 on shaft 35. Shaft 23 carries bevel-gear 31, which meshes with bevel-gear 33 on shaft 34. At the inner extremities of shafts 34 35 are the bevel-gears 36 37, which mesh with bevel-gears, hereinafter to be described, borne on the pivoted cradle-frame and actuating the shafting and connected mechanism carried by the head and tail stocks 4 and 5, mounted on said cradle-frame. The frames 1 and 2 also carry the main revoluble shafts 13 and 14. Upon shaft 13 is mounted the motor-pulley 15, which receives motion from some prime source of power and communicates it to pulley 16 on same shaft 13, which is connected by band 95 with pulley 17 on shaft 14. The shaft 14 has at its extremities sleeved frictional disks 18 19, revolvably mounted in bearings in frames 1 and 2 to rotate with shaft 14, being splined to the latter, so as to have longitudinal motion independent of the same while compelled to rotate with it. The sleeves, which are integral with the disks, are forced outward by springs 110, surrounding the shaft 14 near the bearings, 85 abutting against the extremities of the sleeves outwardly and against collars 109 inwardly, said collars being adjustably secured upon the shaft 14 and both collars and springs being protected by housings 108, borne on shaft 14 90 movably, so as to permit access to the said collars and springs for purposes of adjustment. The object of the spring-pressure on the sleeved disks 18 19 is to give them the requisite frictional adhesion to disks 20 21 in running contact therewith, the latter being mounted on revoluble shafts 22 23, which run in preferably antifrictional bearings in brackets 29 26 27 28, before mentioned. The purpose of the frictional gears is to furnish a variable 95 100

speed to shafts 22 23 and connected gears, varying from zero to the maximum positive and maximum negative revolutions required. To obtain this variable speed under control, 5 the disks 20 21 are splined upon shafts 22 23, so as to have longitudinal motion independent of the same while compelled to rotate with said shafts. To secure said longitudinal motion, the hubs of said disks are grooved and 10 sleeves 24 25, surrounding the shafts 22 23, engage with said grooves by pins or other suitable means. The sleeves are provided with racks 60 61, which are engaged by pinions 58 59 on shafts 68 and 65, respectively, by which 15 said racks are moved up and down at will by means of hand-wheels 62, 63, and 64 on said shafts, shaft 65 being provided with two hand-wheels, one on each side of the machine.

The pivoted cradle-frame 3, which is moved 20 by means of handles 121 to a vertical or horizontal position, as desired, contains the mechanisms which control the various movements of the tail-stock, the rotating heads, the rotary spindle, and plunger, &c., which will now 25 be described. The tail-stock is counterbalanced when the cradle-frame is in the vertical position by weight 119, suspended by rope 118, attached to the tail-stock and passing over pulleys 116 and 117, sustained by pulley- 30 shafts 114 and 115, respectively. The movements of the tail-stock are governed by shaft 22 on the right, Fig. 3, through bevel-gear 32 and driving bevel-gear 37 in mesh with gear 39, which is fast on screw 41. The variable- 35 speed gear 20 governs the speed of revolution of the screw, so that the tail-stock can be moved at any desired speed in either direction, being in engagement with said screw or not at will by means of the half-nut 77 in 40 bracket 78, controlled by lever system 75 76. As shown in Fig. 1, the half-nut is in engagement, and the tail-stock would be traveling when shaft 14 is in rotation. The tail-stock 5 can, however, at all times be moved or ad- 45 justed by hand when out of engagement with the screw by means of handles 120 provided.

The tail-stock carries the rotary hollow spindle 9, plunger 10, and upper holding-head 11, the rotary movements of which are gov- 50 erned by variable-speed gear 21 on shaft 23, as follows: Bevel-gear 31, in mesh with gear 33, rotates gear 36, in mesh with bevel-gear 38, which is fast to spur-gear 43, Fig. 4, but free on shaft 40, with which, however, it can 55 be thrown into engagement at will by means of the clutch member 42. Said spur-gear 43 drives 44, fast on shaft 45, Fig. 4, on which is splined gear 54, Figs. 2 and 7, in mesh with idler-gear 55 on shaft 99, which in turn 60 is in mesh with idler-gear 56 on shaft 100, intermeshing with gear 57, splined upon rev- oluble spindle 9, which it rotates. The tail- 65 stock 5 also carries the sleeve 53, through which the spindle 9 passes and to which is attached the upper holding-head 11. Said

head and sleeve are rotated, by means of gear 48, mounted on said sleeve, through a train of gears 47 46, the latter splined on shaft 40, Fig. 7. The same shaft 40 actuates a train of gears in head-stock 4—viz., 49, idler 50, and gear 51, the latter splined on spindle 8, carrying the lower holding-head 52. These holding-heads thus rotate in unison when motion is imparted to them by means of clutch member 42, which brings shaft 40 into rotation derived from variable-speed shaft 23. Said clutch member is operated by means of clutch-fork 90, Fig. 2, pivoted at 91 and manipulated by a lever 92, Fig. 1. The spindle and plunger thus rotate at different speeds from and independently of the rotative heads, though deriving motion from the same source. The position of lower holding-head 52 relative to the mold is determined by adjustable collars 96 96. The mold 7, borne on carriage 6, is adjusted in position by hand-wheel 86 and shaft 87, the latter carrying a pinion 88, in mesh with fixed rack 89.

The spindle 9, connected with the upper holding-head, is tubular throughout its entire length and terminates below the head 11 in the plunger 10. This plunger is perforated with air-holes 125 for supplying air to the hollow glass cylinder in process of formation. This air-supply is furnished from an outside source under compression through pipe 79, air-regulating valve 80, flexible tube 12, nipple 85, rotative collar 81, air-groove 124, and apertures 83, connecting with tubular passage 82 in spindle. 84 is the cap closing the end of hollow spindle 9. The holding-heads are detachable from their respective spindles in order to remove the glass product. The means is shown enlarged in Figs. 5 and 6. A slotted hub 105 on the holding-head has projecting ledges 104, which fit into flattened grooves 127 formed in the spindle end. A clamp-screw 126 confines the hub in place on the spindle. The holding-heads are roughened or corrugated on their inner faces to give holding and sealing power when applied to the plastic glass, so as to cause the cylinder to rotate and to prevent the escape of the inclosed air. Pins or headed projections 73 are also em- 115 ployed for the same purpose, and these de- vices may be of any shape or design which is found efficient for the purpose. Perforations, recesses, and channels are also a full equivalent.

Operation: Suppose the machine at rest with 120 the cradle-frame 3 in the position shown in Fig. 1. Power is applied to motor-pulley 15 and shaft 13. The cradle-frame is now placed in the position shown in Fig. 2. The mold-carriage 6 and mold 7 are brought to the po- 125 sition shown in Fig. 2, the tail-stock 5 and its supported parts still occupying the position shown in Fig. 1 or thereabout. The plunger 10 is in rotation, the top and bottom holding- 130 heads 11 and 52 are at rest, the clutch mem-

ber 42, Figs. 2 and 4, being still disengaged from its corresponding member. The screw 41 is in rotation through its train connection with rotating shaft 14; but as the half-nut 77 is out of mesh with it the tail-stock 5 remains stationary, counterbalanced by weight 119. The lower holding-head 52 occupies the position relative to the mold shown in Fig. 2. Melted glass is now brought to the machine 10 by any of the appliances usually employed for handling plastic glass from glass-furnaces and a sufficient charge is flowed into mold 7. The hot glass adheres to the roughened or corrugated face of lower holding-head 52, which 15 by reason of its thinness soon reaches a high temperature, but the mold being more massive is not so readily heated to the high temperature of the molten charge and the inner walls being smooth and polished no adhesion occurs. 20 The tail-stock 5 is now lowered by hand until the plunger 10, all the time in rotation, passes down through the charge of molten glass in the mold, leaving but a thin pellicle of glass between it and the lower holding-head, and 25 the stationary upper holding-head 11 beds its roughened or corrugated face in the plastic glass, quickly uniting itself thereto. As soon as firm adhesion of the lower and upper holding-heads has been secured both are set in rotation simultaneously and at the same rate by 30 means of lever 92, throwing clutch member 42 and setting shaft 40 in rotation with its connected gears, carrying with them the mass of plastic glass. In practice the holding-heads 35 are first artificially heated to a dark-red heat to insure the proper adhesion of the plastic glass, and they may be further prepared by an application of molten glass to the roughened or corrugated faces in a manner analogous to 40 the preparation of punties in hand glass-blowing for fire-finishing. The mold is also slightly heated at first to avoid chilling the charge too much, but needs no further heating and, in fact, as the work progresses will require to 45 be artificially cooled to avoid danger of adhesion to the casting. The holding-heads require reheating for each operation. The high speed of rotation of the plunger in excess of that of the rotating heads prevents adhesion to the 50 plastic charge, although fully exposed to the high temperature thereof, and this rotation by a simple change of gearing may be opposite to that of the rotating glass and be fully within the scope of the present invention. The 55 cradle-frame is now returned to a horizontal position by hand. The mold is moved back toward head-stock 4 and off from the rotating mass of glass by means of the hand-wheel 86, pinion 88, and rack 89. Compressed air is 60 now admitted to the interior of the mass of rotating glass in graduated measure by means of the air-valve 80, and simultaneously the tail-stock 5 is started on its outward travel by means of the handle 75, actuating half-nut 65 77 and bringing it into engagement with ro-

tating screw 41. The speed of travel of the tail-stock and rotating head 11 is carefully controlled by means of hand-wheel 62, operating the variable gear 20. This travel gradually elongates the rotating cylinder of plastic glass, while at the same time the admission of compressed air expands the same diametrically, enlarging the volume of the cylinder in all directions, thinning its walls and stretching them equally in all directions, whereby a brilliant surface inside and outside is imparted thereto. The expanding cylinder of glass is prevented from sagging and deformation under the influence of gravity by the graduated rate of rotation 70 imparted to it by its holding-heads. These several correlated movements are throughout the operation thoroughly under the control of the skilled operator by the agency of the hand-wheels, which regulate the variable-speed gears, the air-valve 80, and the clutch-lever 92. When the cylinder of glass reaches the desired dimensions and is sufficiently cool, the operation can be instantly stopped by these agencies and the cylinder 80 removed from the machine by detaching the holding-heads from their respective fastenings. The holding-heads are detached from the glass by means familiar to the art of glass-working. The same is true regarding the 85 slitting and flattening of the glass cylinder when it is desired to convert it into a flat sheet of window-glass.

By this machine much larger masses can be manipulated than in the art of cylinder-glass 90 blowing by manual skill, and consequently larger sheets can be obtained with all the perfection and uniformity due to the aid of machine processes. The magnitude of output and consequent economy of manufacture is 95 one of the signal advantages gained by this as in most other successful substitutions of machine for hand processes, and the uniform stretching of the glass surface in all directions during the process gives a brilliancy 100 and luster, vieing with that obtained by the more expensive methods hitherto employed for making glass in large sheets.

I claim and desire to secure by Letters Patent—

1. A mold for plastic glass, pivotally mounted, whereby said mold may be swung from a vertical to a horizontal position, when charged with plastic glass, means for removing the mold from the charge, and means for simultaneously expanding and stretching the plastic glass while in the horizontal position.

2. A bottomless cylindrical mold for plastic glass, two rotary disk-shaped holding-heads formed on their contacting faces for making 115 secure adhesion to the plastic mass of glass at its ends, whereby the same may be stretched and rotated, means for removing the mold lengthwise from the glass, while the latter is held by the holding-heads, and means for 120

125

130

simultaneously stretching, rotating and expanding the plastic glass while in the horizontal position.

3. A bottomless cylindrical mold, disk-shaped holding-heads for plastic glass revolvably mounted at each end of said mold, and means for permitting one of said holding-heads to be brought into forcible contact with the plastic glass in the mold, said holding-heads being formed on their contacting faces to make adhesion to the plastic glass.

4. A bottomless cylindrical mold, disk-shaped adhesive holding-heads for plastic glass facing the mold at both its open ends, means for forcibly causing adhesion between said holding-heads and the plastic glass, a movable hollow plunger perforated near its terminus, axially located with reference to the mold, and means for advancing the plunger centrally through the plastic mass of glass while held between said holding-heads.

5. A bottomless cylindrical mold, rotatory holding-heads for plastic glass, in axial alinement, projecting into the open ends of said mold, one of which is movable lengthwise, a movable hollow rotatory plunger axially located with reference to the mold and holding-heads, perforated near its terminus, means for independently rotating said plunger, means for admitting air through the plunger, and means for thrusting the plunger centrally through the plastic glass in the mold, down to the opposite holding-head, leaving a thin pellicle of undisplaced glass between it and said opposite holding-head.

6. Two disk-shaped holding-heads for plastic glass having adhesively-formed contacting faces, means for rotating the same in unison, a bottomless cylindrical mold between said heads, means for advancing and retracting one of the said holding-heads while both are in rotation, a hollow spindle axially alined with reference to the movable holding-head and the mold, a plunger within said spindle, and means for rotating said spindle and plunger independently of the heads and at relatively different speeds.

7. A bottomless cylindrical mold for casting a cylinder of plastic glass, disk-shaped holding-heads formed for making secure contact with said glass at both ends thereof, means for rotating said cylinder and adhering holding-heads in unison, a hollow perforated movable plunger, means for forcing said plunger centrally into the plastic cylinder of glass while rotating, means for rotating said plunger independently of the rotatory heads at relatively different speeds, means for separating said heads, and means for introducing compressed air in regulated quantity through said plunger within said rotating cylinder of glass, whereby the latter is expanded and thinned in its walls, while in rotation.

8. A means for casting a cylinder of plastic glass in a vertical position, disk-shaped hold-

ing-heads formed for making secure contact with said glass, at both ends, axially alined, means for rotating said heads and cylinder in unison, means for turning said heads and cylinder to a horizontal position while rotating, means for separating said heads at graduated speed while rotating, whereby the cylinder is stretched and extended, and means for introducing compressed air within the plastic cylinder in graduated quantity while rotating in the horizontal position, whereby the cylinder is expanded and thinned in its walls while being extended.

9. A rotatory spindle, and a holding-head for plastic glass removably secured thereto, said holding-head being formed of a thin metallic plate suitably roughened and prepared on its contacting face for obtaining secure adhesion to the plastic-glass casting to which it is to be applied.

10. A driving-shaft, fixed bearings for the same sleeved frictional disks on the ends of said shaft, outside the bearings, means to press said disks outward on the shaft while rotating, vertically-placed rotatory shafts outside said frictional disks, edge-contact disks splined on said vertical shafts, means for moving said edge-contact disks up and down across the face of the sleeved disks while both are in rotation, whereby variable speed is produced in said vertical rotatory shafts at will, means for rotating the plastic glass, gears and shafting connecting one of said variable-speed mechanisms with the mechanism for rotating the plastic glass, and separate gears and shafting connecting the other variable-speed mechanism with the mechanism for stretching the plastic glass while in rotation.

11. Two rotatory disk-shaped holding-heads for plastic glass in axial alinement, means for rotating the same in unison, a bottomless cylindrical mold in axial alinement with said rotatory heads, of a diameter to fit the same, a carriage for said mold, and means for moving said carriage and mold parallel to the axis of the rotatory heads, whereby said mold may be withdrawn lengthwise from the casting to permit the same to be expanded.

12. Two rotatory holding-heads for plastic glass, in axial alinement, means for rotating the same, a driving-shaft, a variable-speed gear, a hand-wheel, with mechanism for controlling the variable-speed gear, and a system of gears and shafting between said variable-speed gear and said rotatory holding-heads, whereby the latter are rotated in unison and at variable regulated speeds under control of the operator.

13. A pivoted cradle-frame, two rotatory holding-heads for plastic glass, in axial alinement, mounted on said frame, a rotatory shaft concentric with the pivot of said frame, gears on the ends of said shaft, a variable-speed gear in engagement with the outer gear of said shaft, means for controlling said variable-

speed gear, a train of gears and shafting between the inner gear on said shaft and said rotatory heads, whereby the latter are rotated in unison and at variable regulated speeds, 5 while permitting oscillatory movement of the cradle-frame, and a clutch for connecting and disconnecting said gear-train to control the period of rotation of the holding-heads and plastic glass held by them.

10 14. Two rotatory holding-heads for plastic glass, in axial alinement, a driving-shaft, a frictional variable-speed gear actuated by said driving-shaft, a hand-wheel and mechanism for controlling said variable-speed gear, a movable tail-stock carrying one of said holding-heads, a rotary screw connected by gearing with said variable-speed gear, means for connecting and disconnecting said screw with said movable tail-stock, whereby the movements 15 of the latter and its holding-head are controlled and regulated to stretch the plastic glass while rotating, and means for rotating said holding-heads in unison and at variable and regulated speeds simultaneously with the 20 stretching operation.

15 15. Two rotatory disk-shaped holding-heads for plastic glass, in axial alinement, means for rotating said holding-heads in unison, a bottomless cylindrical mold between said holding-heads, a hollow plunger in axial alinement with said holding-heads, means for longitudinally advancing said plunger, means for rotating said plunger independently of the rotating heads, means for introducing compressed air in graduated measure through the plunger, means for removing the mold lengthwise from the glass casting while the latter is rotating between the holding-heads, and means for separating the holding-heads at graduated 30 speed while in rotation with the cast of plastic glass, simultaneously with the introduction of compressed air within the casting through the plunger, whereby the plastic casting is simultaneously extended, expanded, and thinned 40 in its walls while in rotation between the rotating holding-heads, substantially as specified.

16. A main frame, a pivoted cradle-frame, two rotatory holding-heads for plastic glass 50 borne on said cradle-frame, in axial alinement, means for rotating said holding-heads in unison, a bottomless cylindrical mold between said holding-heads, a rotatory hollow spindle in axial alinement with said holding-heads, a perforated hollow plunger on the end of said spindle, means for longitudinally moving said spindle and plunger, means for rotating said spindle and plunger independently of the rotating heads, means for introducing compressed air in graduated measure through said spindle and plunger, means for removing the mold lengthwise from the casting, and means for separating the holding-heads at graduated speed while rotating with the plastic glass cast 60 in the mold, simultaneously with the intro-

duction of compressed air within the casting through the plunger, whereby the plastic casting is simultaneously extended, expanded, and thinned in its walls while in rotation between the holding-heads, substantially as specified. 70

17. A main frame, a cradle-frame pivoted thereon, a head-stock stationary on said cradle-frame, a tail-stock movable on said cradle-frame, a mold-carriage and mold movable on said cradle-frame, a rotary spindle mounted on said head-stock, with means for rotating the same, a holding-head on said head-stock spindle, a tubular rotary spindle mounted on the tail-stock in axial alinement with said head-stock spindle, with means for rotating the same, a holding-head concentric with said tubular spindle, a perforated plunger on the end of said tubular spindle, means for introducing air under compression in graduated measure through said tubular spindle and perforated plunger while rotating, and means for moving said tail-stock with its spindle and holding-head at variable speed away from said head-stock and its holding-head while the holding-heads are rotating, substantially as specified. 80

18. A main frame, a cradle-frame pivoted on said frame, a stationary head-stock on said cradle-frame, a rotary spindle on said head-stock, a holding-head on said spindle, a movable tail-stock on said cradle-frame, a rotary sleeve on said tail-stock, a holding-head on said sleeve, a tubular rotary spindle passing axially through said sleeve, in axial alinement with the head-stock spindle, a perforated plunger on the end of said tubular spindle, a means for introducing compressed air in graduated measure through said tubular spindle and plunger while rotating, a variable-speed gear for moving the tail-stock back and forth at will, a means for connecting and disconnecting the movable tail-stock with the variable-speed gear at will, a variable-speed gear for rotating the holding-heads in unison, a means for connecting and disconnecting the rotative holding-head mechanisms with the said variable-speed gear at will, an independent gear-train borne on the movable tail-stock for rotating the tubular spindle and plunger independently of the rotative holding-heads, in gear connection with the said variable-speed gear for moving said tail-stock, a mold-carriage on the cradle-frame, and means for moving said mold-carriage back and forth in lines parallel with the rotary spindles, substantially as specified. 100

19. A pivoted cradle-frame, a revoluble spindle on said frame, a holding-head for plastic glass detachably held on said spindle, a revoluble sleeve longitudinally movable on said frame, in alinement with said spindle, a holding-head for plastic glass detachably held on said sleeve, a hollow spindle with perforated extremity concentrically held within said sleeve, independently revoluble therein, means 115

for revolving said holding-heads in unison, means for introducing compressed air through the rotary hollow spindle, a cylindrical open-ended mold between said revoluble holding-heads, and means for moving the mold lengthwise, substantially as specified.

In testimony whereof I have signed my name

to this specification in presence of two witnesses.

IRVING W. COLBURN.
